SNAP-ON PERFORATED SHAKER DISK FOR
CONDIMENT CONTAINER AND CLOSURE
CAP OVER SAID DISKEdward A. Randlett, Baltimore, Md., assignor to
Owens-Illinois Glass Company, a corporation
of Ohio

Application June 8, 1948, Serial No. 31,618

10 Claims. (Cl. 222—499)

1

My invention relates to a bottle or container for condiments or other powdered or granulated materials, provided with a closure and a perforated shaker disc through which the materials are dispensed.

An object of the invention is to provide an article of this character provided with a removable cap or closure and a novel form of perforated shaker disc which is retained in position on the container when the cap is removed, thereby permitting the contents of the container to be dispensed through the shaker disc, the said disc being readily removable from the container independently of the closure cap.

A further object of the invention is to provide a combined closure cap and perforated shaker disc frictionally or removably held within the cap before the latter is placed on the container and which disc, when the cap is screwed into position, is automatically attached to the container, permitting the cap to be removed without detaching the disc from the container.

A further object of the invention is to provide a container with a closure cap and a perforated shaker disc within the cap and which serves as a sealing gasket when the cap is applied to the container and which remains attached to the container in operative position when the cap is removed.

Other objects of the invention will appear hereinafter.

Referring to the accompanying drawings:

Fig. 1 is a part sectional side elevation of a shaker device embodying my invention, parts of the structure being broken away;

Fig. 2 is a fragmentary sectional elevation of the same on a somewhat larger scale;

Fig. 3 is an elevation view of the shaker tilted to position for dispensing its contents, the cap being removed and a portion of the shaker disc being broken away;

Fig. 4 is a bottom plan view of the shaker disc.

The shaker comprises a bottle 5 or container, closure cap 6 and shaker disc 7. The cap comprises a circular top 8 and a depending marginal skirt or flange 9. The cap may be attached to the container by any suitable or conventional means, the cap being preferably either of the snap-on type or screw-threaded type. As shown the neck of the container is formed with a spiral thread 11 or bead which cooperates with a screw thread 12 formed on the interior surface of the cap skirt 9, for removably securing the cap on the container.

The shaker disc 7 is in the form of a flat circular disc provided with a multiplicity of per-

2

forations 13 distributed thereover. The disc may be of slightly less diameter than the interior diameter of the skirt 9 and fits against the flat bottom or inner surface of the top 8 of the cap. The disc is preferably made of an elastic, compressible, rubber-like material which makes sealing contact with the top surface 14 of the container neck and also makes sealing contact with the inner flat surface of the cap top 8. The disc 7 may be made of polythene which I have found is particularly adapted for the purpose of my invention. The disc 7 may have a frictional fit within the cap, or may have its outer diameter somewhat greater than the inner diameter of the screw thread 12 so that when the disc is assembled with the cap, it is retained therein.

In order to attach the disc 7 to the container neck when the cap is screwed into position on the container, the following construction of the disc and container neck is provided. The disc is formed with an integral, depending marginal flange 15 extending throughout its circumference, the flange having formed on its inner surface an annular bead 16. The inner surface of the bead as shown in cross-section is substantially V-shaped and has a downwardly and inwardly inclined or tapered surface 17, below which is a downwardly and outwardly inclined or flared surface 18. The bottle neck is formed with a correspondingly shaped circumferential groove 19 to receive the bead 16. The groove 19 is closely adjacent to the top surface of the container neck, thereby providing an annular rib or bead 20 the lower surface of which is tapered, and against which the surface 17 of the bead 16 bears when the disc 7 is attached to the container neck. A circumferential groove 22 or fillet is formed in the disc 7 at the junction of the flange 15 and body of the disc, thereby providing a comparatively narrow neck portion uniting the bead 16 with the body of the disc. This construction permits the flange 15 with the bead 16 to swing outwardly over the rib 20 as the disc is forced downwardly onto the container, the bead 16 then snapping into position in the groove 19.

In assembling the parts the disc 7 is first placed within the cap 6 and is held against accidental removal or displacement as above described. The cap 6 with the disc 7 therein is screwed or moved down into position on the container, this operation depending on the particular type of attaching means employed. As the cap is thus brought down into position the disc 7 is carried downward into sealing engagement with the container neck, the bead 14 snapping into position as above

described. The container is thus closed and sealed.

When it is desired to dispense the contents of the container, the closure cap is unscrewed or removed while the shaker disc 7 remains securely held in place by the interlocking engagement of the beads 16 and 20. The contents of the container may then be dispensed by shaking the container as is indicated in Fig. 3. The shaker disc may readily be removed when desired for 10 refilling the container, or for other purpose. When the closure cap is placed on the container, the disc 7 makes a hermetic seal between the container neck and cap, thereby protecting the contents of the container.

Modifications may be resorted to within the spirit and scope of my invention.

I claim:

1. The combination of a shaker disc formed with perforations therethrough at points distributed over the surface of said disc, the disc having a marginal depending flange formed with means on its inner surface for attachment to a container, and a closure cap having a depending marginal skirt formed on its inner surface with a spiral thread or bead, said disc being seated within said cap and of greater diameter than that of the cap skirt at the inner surface of said thread and thereby holding the disc within said cap.

2. A shaker comprising a container having an open circular neck, a shaker disc seated on said neck and formed with a multiplicity of perforations through which powdered contents of the container may be dispensed, said neck being formed with an annular bead on its exterior surface adjacent to the top surface of the neck, said disc having a marginal skirt formed with a circumferential bead on its inner surface, said circumferential bead engaging beneath the first-mentioned bead and holding said disc in sealing contact with the container neck, said disc consisting of flexible, resilient, elastic material and being formed with an annular interior groove at the upper edge of the skirt thereby permitting the bead on the disc to expand and spring past the said bead on the container neck when the disc is placed on top of the neck and downward pressure applied to bring the disc to sealing position on the container, a closure cap comprising a circular top seated on the disc in sealing contact therewith and having a marginal depending skirt, and means for removably attaching the cap to the container and permitting the cap to be removed while the disc is held in position on the container neck.

3. A shaker comprising a container having an open circular neck, a shaker disc seated on said neck and formed with a multiplicity of perforations therethrough, said neck being formed on its outer surface with an annular neck bead at the upper end of the neck, said disc having a skirt formed with a circumferential bead on its inner surface of smaller inner diameter than the outer diameter of the neck bead and engaging beneath the neck bead and holding the disc in sealing contact with the container neck, the disc consisting of resilient elastic material permitting the bead on the disc to expand and spring past the neck bead when the disc is pressed downward to sealing position on the container neck, a closure cap comprising a circular top seated on the disc in sealing contact therewith and having a marginal depending skirt, the container neck and cap skirt being formed with

cooperating screw threads positioned below the disc and said beads for the attachment of the cap to the container and for causing the disc to snap into said sealing position on the container neck when the cap with the disc therein is screwed into position on the container, the inner diameter of the screw thread on the cap skirt being less than the exterior diameter of the disc whereby the disc and cap are held in assembled relation before being applied to the container and permitting the parts to be assembled by screwing the cap into position on the container after the disc has been assembled with cap, the disc being held in position on the container neck 15 when the cap is unscrewed and removed from the container.

4. A shaker comprising a container having an open circular neck, a shaker disc seated on the neck in sealing contact therewith and formed with a multiplicity of perforations through which powdered contents of the container may be dispensed, said neck formed at its upper end with an exterior annular bead and an annular recess immediately below said bead, said disc being 20 formed with an integral marginal skirt depending therefrom, the skirt having formed on its inner surface an annular bead engaging and fitting within said annular recess, the disc being shaped to provide an annular, interior groove 25 at the upper edge of the skirt, the beaded portion of the said skirt being flexible outwardly to permit the bead to expand and snap over the bead on the container neck when downward pressure is applied to the disc, and a closure cap 30 comprising a circular top fitted on the disc and a marginal depending skirt, the container neck and the cap skirt being formed with cooperating screw threads on their exterior and interior surfaces respectively, the inner diameter of the screw thread on the cap skirt being less than the exterior diameter of the disc whereby the disc and cap are held in assembled relation before being applied to the container and permitting the parts to be assembled by screwing the cap into 35 position on the container after the disc has been assembled with the cap, the disc being held in position on the container neck when the cap is 40 unscrewed and removed from the container.

5. A combined sealing liner and sifter cap for 45 a condiment container provided with a mouth having an undercut peripheral lip and having a threaded neck portion to receive a closure cap, said combined liner and sifter cap comprising an elastic rubber-like body having a central perforated disc portion with a depending continuous flange around its periphery, whereby the same may be snapped and retained over the mouth of said container, said disc portion being 50 adapted to provide a seal between the mouth of the container and the closure cap.

6. The combination with a container having an externally-threaded neck portion to receive a closure cap and having a peripherally undercut lip at the mouth thereof, of a dispensing cap 55 formed of a slightly resilient rubber-like material fitted over said lip and stressed so as to be removably held thereon, said dispensing cap having a perforated flat disc area covering the mouth of the container and having a depending flange encircling the undercut lip of the container and of an internal diameter such that the flange is under slight tension when the dispensing cap is 60 on the container.

7. The combination defined in claim 6 wherein 75 there is a removable closure cap screwed onto

the threaded neck of the container having an interior surface which bears against the top of the dispensing cap above the lip of the container and which presses against the dispensing cap to form a seal around the lip of the container.

8. The combination with a container having an externally-threaded neck portion to receive a closure cap, said container having a peripherally undercut lip at the mouth thereof providing a downwardly tapered surface surrounding the container immediately below the top surface of the neck, a dispensing cap formed of a slightly resilient rubber-like material fitted over said lip, said dispensing cap comprising a flat disc forming the body thereof and covering the mouth of the container, the disc being formed with dispensing openings therethrough and having a depending flange encircling the undercut lip of the container, said flange being formed with an inner downwardly tapered surface bearing against said tapered surface on the container, said flange being of a diameter to provide a snap-on fit on the container.

9. The combination defined in claim 8 wherein there is a removable closure cap screwed onto the threaded neck of the container having an interior surface which bears against the top of the dispensing cap above the lip of the container and which presses against the dispensing cap to form a seal around the lip of the container.

10. The combination of a shaker disc and a container, said shaker disc consisting of resilient, flexible material and comprising a flat circular body with a multiplicity of perforations therethrough distributed over said body and a circumferential flange depending vertically from said body and of substantially uniform exterior throughout, said flange formed on its inner surface with an annular bead, said bead having a downwardly tapered upper surface and an upwardly tapered lower surface, said container having an open circular neck formed on its exterior surface with an annular bead at the upper end thereof shaped to engage over the said bead on

the disc flange, the inner diameter of the bead on the disc flange being less than the diameter of the neck bead, said disc being formed with a circumferential groove in its inner surface at the junction of the said flange with the body of the disc, thereby forming a comparatively thin neck portion uniting the body of the disc with said bead of the disc and permitting the latter to be flexed outwardly and its diameter expanded for attaching it to the container in sealing contact with the top surface of said container neck, and an imperforate closure cap having a screw threaded connection with said neck and thereby held seated on said disc, in sealing contact therewith, the internal diameter of said cap at the inner surface of said thread being less than the diameter of said disc whereby said cap and disc are held in assembly relation before being applied to the container.
